AUTOMATIC IGNITION CUT-OFF WHICH OPERATES WHEN OILING SYSTEM CEASES TO FUNCTION

Albert Thibault, Bonne Madone, Saskatchewan,
Canada

Application December 6, 1932, Serial No. 645,899

1 Claim. (Cl. 123—146.5)

This invention relates to all internal combustion motors equipped with pump or other forced oiling system, and has for an object, to provide means whereby the ignition circuit will be automatically broken in the event of pump or forced oiling system refusing to function due to mechanical disability or any other cause.

10 A further object of the invention is to provide a novel oil pressure controlled switch which will automatically cut off the ignition should the pump or forced oiling system refuse to function.

A still further object is to provide a simple oil pressure controlled switch, inexpensive to construct, which will not easily get out of order.

15 With these and other objects in view the invention consists in certain novel details of construction and combination of parts hereinafter fully described and claimed, it being understood that various modifications may be resorted to 20 without sacrificing any of the advantages of the invention.

In the accompanying drawing forming part of these specifications, Fig. 1 shows a view of an internal combustion motor with my invention attached as it would appear when in a position for 25 starting the motor.

Fig. 2 shows a view of the invention when the motor is running and the oil functioning.

Fig. 3 shows a view of the invention when the 30 oil ceases to flow and the device is in position to cut off the ignition and stop the motor.

Fig. 4 is a longitudinal section of the cylinder. Referring to the drawing in which like characters of reference designate similar parts in the 35 various views, "B" designates the distributor of the ignition system thereof and in these specifications the term oil pump is used. It is to be understood however, that my invention is as applicable to magneto systems of motor ignition as 40 to distributor and coil systems and also to motors where the oil pressure is furnished by other mechanical devices than pumps.

In order that the general relations and assembly 45 of parts may be readily understood I have indicated in Fig. 1 an internal combustion motor with the oil filler neck "A"; the distributor "B"; the dash panel "C"; the starter pedal "D"; the oil line from the motor to the gauge on the dash panel "B".

50 The device is illustrated in the drawing in which I is a bracket formed from a piece of metal shaped to fit snugly to the motor and held in position by the stud bolts which hold the cylinder head to the block, and to this is attached the working parts of my invention.

A cylinder 4 of suitable size is attached to the bracket 1, and within the cylinder is a piston 5 and a piston stem 6, which projects through the upper end of the cylinder and a spiral spring 7, which is coiled about the piston stem 6 and interposed between the piston 5 and the upper end of the cylinder. 5

The cylinder head 8 is screwed on to the bottom end of the cylinder and is removable. It is provided with a nipple to which is attached the oil line 9 which is connected by a T joint 10 to the oil line "E" of the motor which connects to the gauge on the dash panel "C". The cylinder is also provided as shown with a nipple to which is attached the pipe 11 connecting to the oil 15 filler neck "A", and thus provides for the return of any oil that is forced past the piston 5 to be returned to the source of supply. 10

The breaker arm 16 is a metal arm which is attached to the bracket 1 by a bolt or pin and moves freely on the same and on the under side 20 has a notch 17.

The breaker arm lifter and latch 15 is attached to the bracket 1 by a bolt or pin and moves freely on same. The forward part is pointed so 25 that when raised it will fit into the notch 17 in the breaker arm 16 and hold it up as shown in Fig. 1. Attached to the breaker arm lift is the rod 12 which passes to dash panel "C". There is a retard spring 13, one end of which is attached to 30 the rod 12 and the other to the dash panel "C".

The rod 14 is attached to the starter pedal "D" and the forward end passes through a guide which is formed by bending part of the bracket 1 at 35 right angles and punching a hole through it. 35

The rod 14 is attached to the starter pedal "D" in such a way that when the starter pedal is pressed the rod is shoved forward and presses against the breaker arm lift.

An insulated point 2 is fastened to the bracket 40 1 and an insulated cable connects this point with the distributor "B".

In starting the motor by cranking the rod 12 is shoved forward and the breaker arm lifter 15 raises the breaker arm 16 and the forward part 45 of the breaker arm lifter 15 fits into the notch 17 in the lower side of the breaker arm 16 and latches it up in the position shown in Fig. 1 so that the contact between the breaker arm 16 and the insulated point 2 is broken. When using the self starter when the starter pedal is pressed the rod 14 is forced forward and pressing on the breaker arm lifter raises it and latches it up. 50

When the motor starts the oil pressure from the pump causes the oil to flow through the pipe 55

9 into the cylinder 4 and impinges on the piston 5 and causes the piston and piston stem 6 to rise. The piston stem on rising raises the breaker arm 16 and the breaker arm lifter 15 is released and 5 the retard spring 13 draws the rod 12 back and the breaker arm lifter returns to the position shown in Fig. 2.

Should the pressure in the oil line at any time fail, due to oil being too low or to the oil pump 10 ceasing to function the spring 7 will force the piston 5 and the stem 6 downward and the breaker arm will come to the position shown in Fig. 3 and will make contact with the insulated point 2 and cut off the ignition and stop the motor.

15 I claim:

In combination, an internal combustion engine with ignition and starting means and oil pres-

sure lubrication, and a device for grounding the ignition current in case of failure of oil pressure, said device comprising a bracket adapted for attachment to the engine casing, a grounded elbow lever pivotally mounted on said bracket, an insulated ignition contact supported by said bracket and adapted for engagement with a part of said lever, said lever having a notch adapted for engagement by a second lever also pivotally mounted on said bracket, and second lever adapted to 5 be actuated to disconnect said elbow lever from said contact during engine starting, together with an oil pressure device mounted on said bracket, and adapted only when actuated by said oil pressure to move said elbow lever away from 10 said ignition contact.

ALEBERT THIBAULT.
